ERNST WITTLAKE, OF HANOVER, GERMANY.

TRAIN CONTROLLING AND SIGNALING SYSTEM.

1,047,474.

Specification of Letters Patent. Patented Dec. 17, 1912.

Application filed June 14, 1912. Serial No. 703,598.

To all whom it may concern:

Be it known that I, ERNST WITTLAKE, a citizen of the Empire of Germany, residing at Hanover, in the Empire of Germany, have invented a new and useful Train Controlling and Signaling System, of which the following is a specification.

My invention relates to a device for automatically stopping any locomotive, that happens to have run past a semaphore or other signal while it is at "danger" or indicates the block to be closed. A normally closed main circuit is disposed on the locomotive and includes a battery and an electromagnet, the armature of which latter when released is adapted to close a signal-circuit shunted to the battery. Two fuse blocks are inserted in the two parts of the main circuit between the battery and the electromagnet and an open circuit shunted to the electromagnet is adapted to be closed by means of a lever movable on the locomotive on being struck by any of a number of operating disks distributed over the track, when the operating disk connected with the semaphore or other signal is moved into the path of the said lever, whereby the main circuit is short-circuited, so that the two fuse blocks are burned out, whereby the main circuit is opened and consequently the electromagnet becomes without current and its armature now released closes the signal circuit. The signal circuit is connected in multiple with optical signals, alarms and a solenoid controlling the air-brake apparatus of the locomotive, so that on the main circuit being opened the current of its battery will circulate in the signal circuit, whereby not only both the optical signals and the alarms are actuated, but also the air-brake apparatus is set to operate for stopping the locomotive or train. After replacing the molten fuse blocks by fresh ones the device is again ready for work. An interrupter is also disposed on the locomotive so as to enable the driver to open the main circuit in case he is aware of the semaphore or other signal being at "danger," so that the fuse blocks are saved.

I will now proceed to describe my invention with reference to the accompanying drawing, in which—

Figure 1 is an elevation of the rear part of a locomotive provided with the said device and of a mechanism connected with some semaphore or other signal for mov-

ing an operating disk into and out of the path of a lever movable on the locomotive, and Fig. 2 is a diagram of the device.

Similar characters of reference refer to 60 similar parts in both views.

1 is a chain wheel, which is supported by a suitable standard 2 and is connected by means of a chain 3, 3 with some semaphore or other signal of any known construction (not shown). The chain wheel 1 is shown to have a pin 4, which is connected by means of a chain 5 passing over suitable guiding rollers 6 and 7 with the weighted rear arm 8 of a lever 9 fastened on a shaft or pin 10. 65 rocking in a support 11 disposed in some box 12 in the soil. Through the cover 13 of the box 12 a rod 14 is vertically guided, which is below pivotally connected with the lever 9 by means of a pin 15 engaging in a 70 slot 16 at the free end of the lever. On the upper end the rod 14 carries an operating disk 17. 75

On the frame of each locomotive L is disposed a suitable casing 18, in which a shaft 19 is mounted to rock. This shaft has fastened on it a lever 20 below and a contact arm 21 above, the free end of which latter is connected by a helical spring 23 with a pin 24 in the casing 18. On opposite sides of 80 the shaft 19 two contact pieces 25 and 26 are fastened within the casing 18 and are insulated therefrom. When the respective semaphore or other signal is at "safety," it will have by the chain 3 so turned the 85 chain wheel 1, as to raise by means of the rope 5 the weighted arm 8, so that the other arm 9 is lowered and by the rod 14 the operating disk 17 is also lowered and thus moved out of the way of the lever 20 of 90 any locomotive. The helical spring 23 tends to move the upper arm 21 and therewith the lever 20 into the vertical middle position shown, so that when the locomotive L moves in either direction over the operating disk 17 the lever 20 will not strike this disk but maintain its normal position shown. When, however, the semaphore or other signal is at "danger," the chain wheel 1 will have been turned into the position shown; so 95 that the weighted arm 8 occupies its lower position shown and the operating disk 17 is raised and engages in the path of the lever 20. In consequence of this the operating disk 17 will strike the lever 20 and turn it 100 into the extreme left position 20a (Fig. 2), in case the locomotive L runs from left to

right, or turn the lever 20 into the extreme right position 20^b, in case the locomotive runs from right to left. Fastened on the free end of the arm 21 is a contact piece 22, which is adapted to come in contact with the right contact piece 26 for the position 20^a of the lever 20 and with the left contact piece 25 for the position 20^b of the lever. On the locomotive L is disposed a battery 30, which is connected with an electromagnet 29 by two conductors 31 and 32, the parts 29, 30, 31, 32 forming a main circuit, which is normally closed. The conductor 31 is made in two parts terminating in two poles 33 and 34 of an interrupter I, which two poles are normally connected together by the bow 35 of the interrupter. The bow 35 is provided with a handle 36 of insulating material and can be thereby turned around two poles 37 and 38. When the interrupter I is turned out of contact with the two poles 33, 34, of course the main circuit will be thereby opened. Two fuse blocks 39 and 40 are inserted in the two conductors 31, 32, so that when they melt also the main circuit will be opened. An optical signal 41 may be connected between the two conductors 31, 32, so as to indicate whether the main circuit is closed or not. The above mentioned two contact pieces 25 and 26 are electrically connected together by a conductor 27, which in turn is connected with a conductor 28, that joins to the conductor 31. The shaft 19 is electrically connected with the conductor 32 by a conductor 42. The parts 28, 27, 26, 25, 35, 22, 21, 19, 42 form a normally open circuit shunted to the electromagnet 29.

The armature 43 of the electromagnet 29 is provided with two projections 44, 45, which are adapted to engage in two mercury cups 46, 47, that are connected with the two poles of the battery 30 by means of conductors 48, 49, 50. The parts 48, 49, 46, 44, 43, 45, 47, 50 form a normally open signal circuit shunted to the battery 30. Two optical signals 51, 52 are shown to be connected between the conductors 48 and 49. A solenoid 53 is also disposed on the locomotive and is connected with the conductor 48 by a conductor 54 and with the above mentioned pole 38 by a conductor 55. Three alarms 56, 57, 58 are shown to be connected between the conductor 54 and the pole 37 by means of conductors 59 and 60. In this manner the optical signals 51, 52, the alarms 56, 57, 58 and the solenoid 53 are connected in multiple with the parts 48, 49 of the signal circuit.

The solenoid 53 is to control the air-brake apparatus of the locomotive in any known manner. For example a brass tube 61 is vertically disposed in the axis of the solenoid and is connected with the compressed air tube for the brake cylinders. This tube 61 is beneath the solenoid provided with

holes 62, which are normally closed by the movable iron core 63, when the latter occupies its normal lower position, as is shown. On the solenoid 53 being energized the iron core 63 will be attracted upward and uncover the holes 62, 62, so that compressed air is allowed to escape from the tube 61 into the atmosphere and the air-brake apparatus will set to operate in a known manner.

The device so far described operates as follows: Normally the main circuit 29, 30, 31, 32 is closed, the bow 35 of the interrupter I engaging in the two poles 33, 34, so that the current from the battery 30 circulates in the main circuit and the electromagnet 29 energized attracts its armature 43, whereby the signal circuit is opened. When the locomotive happens to run past the semaphore or other signal while it is at "danger," the lever 20 striking the operating disk 17 will be thereby turned into either extreme position, whereby the open circuit 28, 27, 26, 25, 42 is temporarily closed and consequently the battery 30 is short-circuited, so that the two fuse blocks 39, 40 will melt and the main circuit is opened, therefore the electromagnet 29 becomes without current. The armature 43 now released drops and by engaging with its two projections 44, 45 in the two mercury cups 46, 47 closes the signal circuit 30, 48, 49, 50, so that both the optical signals 51, 52 and the alarms 56, 57, 58 are actuated and at the same time the solenoid 53 is energized for setting the air-brake apparatus to operate, whereby the locomotive or train is stopped. In case the locomotive-driver is aware of some semaphore or other signal being at "danger," he can at once open the main circuit by turning the bow 35 of the interrupter I out of contact with the two poles 33 and 34, whereby the armature 43 is released and the signal circuit is closed, so that the same effects as described above will take place, while the two fuse blocks 39, 40 are not rendered useless but remain ready for work. As long as the signal circuit is closed, the visible and audible signals will prevent the locomotive-driver from forgetting to again close the main circuit in case everything is again in order.

It is obvious, that every semaphore or other signal in the railway system requires to be provided with the mechanism described for moving an operating disk 17 into and out of the way of the lever 20 on any locomotive.

The train controlling and signaling system described can be varied in many respects without departing from the spirit of my invention.

I claim:

1. In a system of the character described, the combination with a vehicle equipped with an air-brake apparatus, of a normally

closed main circuit including a battery and an electromagnet, two fuse blocks in said main circuit between the battery and the electromagnet, a normally open operating circuit shunted to said electromagnet, a spring-pressed lever normally in a middle position and adapted to be turned into either extreme position for closing said operating circuit and thus short-circuiting said battery, whereby said two fuse blocks are molten and then said electromagnet becomes without current, a normally open signal circuit shunted to said battery and adapted to be closed by the armature of said electromagnet when released, said signal circuit being connected in multiple with visible and audible signals, also with a solenoid adapted to set the air-brake apparatus to operate, and means distributed over the railway system and adapted to operate said spring-pressed lever.

2. In a system of the character described, the combination with a vehicle equipped with an air-brake apparatus, of a normally closed main circuit including a battery and an electromagnet, two fuse blocks in said main circuit between the battery and the

electromagnet, a normally open operating circuit shunted to said electromagnet, a spring-pressed lever normally in a middle 30 position and adapted to be turned into either extreme position for closing said operating circuit and thus short-circuiting said battery, whereby said two fuse blocks are molten and then said electromagnet becomes 35 without current, a normally open signal circuit shunted to said battery and adapted to be closed by the armature of said electromagnet when released, said signal circuit being connected in multiple with visible and 40 audible signals, also with a solenoid adapted to set the air-brake apparatus to operate, an interrupter in said main circuit and adapted to normally close said main circuit, said interrupter when opened breaking the main 45 circuit and thus causing said signal circuit to be closed whereby said two fuse blocks are saved, and means distributed over the railway system and adapted to operate said spring-pressed lever.

ERNST WITTLAKE.
